US0D1074811S

(12) United States Design Patent (10) Patent No.: US D1,074,811 S
(45) Date of Patent: * May 13, 2025

(54) LABEL

(71) Applicant: Eli Lilly and Company, Indianapolis, IN (US)

(72) Inventors: Fernando Ludwig Fernandez Marin, Maplewood, NJ (US); Frank N. Hockmuller, Noblesville, IN (US); Yuchen Liu, Flushing, NY (US); Ross Stephen Merkel, Fishers, IN (US); Joseph Vito Primiani, Astoria, NY (US); J Geoffrey Swope, Indianapolis, IN (US)

(73) Assignee: ELI LILLY AND COMPANY, Indianapolis, IN (US)

() Term: 15 Years

(21) Appl. No.: 29/867,534

(22) Filed: Oct. 27, 2022

Related U.S. Application Data

(63) Continuation of application No. 29/838,534, filed on May 13, 2022.

(57) CLAIM

The ornamental design for a label, as shown and described.

DESCRIPTION

The patent or application file contains at least one drawing executed in color. Copies of this patent or application with color drawing(s) will be provided by the Office upon request and payment of the necessary fee.

FIG. 1 is a view of a first embodiment of a label;
FIG. 2 is a view of a second embodiment of a label;
FIG. 3 is a view of a third embodiment of a label;
FIG. 4 is a view of a fourth embodiment of a label;
FIG. 5 is a view of a fifth embodiment of a label;
FIG. 6 is a view of a sixth embodiment of a label; and,
FIG. 7 is a view of a seventh embodiment of a label.
The broken lines show portions of the label that form no part of the claimed design.

The greyscale shading in FIG. 7 represents a contrast in appearance.

1 Claim, 7 Drawing Sheets
